SHOE TOE LIFTER

Filed March 2, 1944

UNITED STATES PATENT OFFICE

2,378,899

SHOE TOE LIFTER

Bert J. Clausen, Huntington Park, Calif.

Application March 2, 1944, Serial No. 524,696

11 Claims. (Cl. 12—128.5)

This invention is a shoe toe lifter, and the general object of the invention is to provide a simple and improved lifting device, which may be inserted in a shoe and under the toe of the shoe, and actuated to lift and stretch the toe boxing, so that said boxing will fit the toe of the wearer of the shoe freely, and permit the shoe to be worn with comfort.

Other objects and advantages will appear hereafter as this specification progresses.

The invention is illustrated in the annexed drawing which forms a part of this specification, and in which

Fig. 1 is a perspective of my invention.

Fig. 2 is a side elevation of my invention shown in position in a shoe for lifting the toe boxing of the shoe, the shoe being shown in vertical longitudinal section.

Fig. 3 is a fragmentary view like Fig. 2 with my invention shown in the act of lifting the toe boxing of the shoe.

Fig. 4 is a top plan view of my invention.

Fig. 5 is a bottom plan view of my invention.

Fig. 6 is a fragmentary vertical longitudinal section of my invention on an enlarged scale with an adjustable engaging member on the lifting end of the lifting arm for increasing the lift of the toe boxing of a shoe.

Fig. 7 is a longitudinal section of my invention taken on line 7—7 of Fig. 6.

Fig. 8 is a fragmentary side elevation of a modification of my invention.

Fig. 9 is a transverse vertical section taken on line 9—9 of Fig. 8.

Fig. 10 is a fragmentary side elevation of another modification of my invention.

Fig. 11 is a horizontal section taken on line 11—11 of Fig. 10.

Fig. 12 is a forward end view of Fig. 10.

Referring more particularly to the drawing in which corresponding parts are designated by the same reference characters in all of the views, my invention includes generally a supporting member 1 and a lifting member 2 pivotally mounted in said supporting member by a pivot 3, which lifting member is normally held in its initial position in said supporting member by a flat spring 4.

The supporting member 1 comprises a base 5 and a handle 6 upstanding from the rear of said base forwardly at an angle of substantially sixty degrees with relation to said base. The base 5 is bifurcated and formed with a pair of spaced forked base arms 7, joined together at the rear end of the base at 8, and, at their lower side, a

bridge 9 extends across the space between the arms 7 and is secured to said arms for the purpose hereinafter described.

The lifting member 2 comprises a lifting arm 10 and a handle 11 upstanding from the rear end of said lifting arm forwardly at an angle of substantially forty-five degrees with relation to said arm. The lifting member 2 is pivoted at the rear end of its lifting arm 10 by the pivot 3 in the crotch 12 in the rear end of the bifurcated base 5 of the supporting member 1, with said lifting arm 10 extending forwardly from its rear pivoted end between the fork arms 7 of said base 5, and with the lower end of the handle 11 of the lifting member 2 positioned forwardly of and adjacent the lower end of the handle 6 of the supporting member 1. The pivot 3 extends transversely through the rear portion of the fork arms 7 of said bifurcated base 5 and through the rear end of said lifting arm 10, and said pivot is secured in said fork arms 7 and is loosely fitted in an opening 13 in said lifting arm 10, so that the lifting member 2 may turn on said pivot. The forward end 14 of the lifting arm 10 is enlarged in width to enlarge the engaging surface of said end. In the lower edge of the lifting arm 10 is provided a notch 15 to receive the bridge 9 in the base 5 of the supporting member 1, so that said bridge will engage the inner wall 16 of said notch to limit the downward movement of the lifting member 2 with the lower edge of said lifting arm 10 flush with the lower surface of the base arms 7 of the supporting member 1.

An adjustable engaging head 17 may be mounted on the forward end of the lifting arm 10 of the lifting member 2 by means of a threaded shank 18 depending from said head and engaging a threaded opening 19 in the forward end of said lifting arm.

While the handle 6 of the supporting member 1 and the handle 11 of the lifting member 2 are positioned adjacent each other at their lower ends, said handles diverge upwardly when the lifting member 2 is in its lowermost and initial position, since the handle 6 extends at an angle of substantially sixty degrees from the base 5 of said supporting member 1, while the handle 11 extends at an angle of substantially forty-five degrees from the lifting arm 10 of said lifting member 2, so that the handle 11 may be swung rearwardly toward the handle 6 to swing the lifting arm 10 upwardly on the pivot 3.

The flat spring 4 is bent V-shape intermediate its ends and is positioned between the handles 6 and 11, with its ends secured by rivets 20 and

21, respectively, to the inner edges of said handles near the upper ends thereof, said spring normally holding said handles apart with the lifting member 2 arrested in its lowermost and initial position by the engagement of the inner wall 16, of the notch 15 in the lower edge of the lifting arm 10 of said lifting member, with the bridge 9 in the base 5 of the supporting member 1.

The operation of my invention is as follows:

The lower part of my toe lifter is introduced into a shoe 25 and is moved forwardly in the shoe until the forward end 14 of the lifting arm 10 rests under the depressed toe boxing 26 of the shoe, the handles 6 and 11 extending upwardly and forwardly out of the shoe through the throat 27 in the front of the upper of the shoe, as illustrated in Figs. 2 and 3 of the drawing. The operator then grasps the handles 6 and 11, and applying pressure to said handles swings the handle 11 rearwardly and the lifting arm 10 upwardly on the pivot 3 against the tension of the spring 4, until the forward end 14 of the lifting arm 10 engages and lifts the toe boxing of the shoe as desired, as illustrated in Fig. 3 of the drawing.

If the upward movement of the lifting arm 10 is not great enough to lift the toe boxing of a particular shoe, the adjustable engaging head 17 may be secured and adjusted on the forward end of said lifting arm by screwing the threaded shank 18 of said engaging head into the threaded opening 19 in the forward end of said lifting arm, which head, being elevated above said forward end of said lifting arm will compensate for the lack of the required movement of said lifting arm and will engage and lift the toe boxing sufficiently upon the limited upward movement of said lifting arms by the handle 11.

In the modification of my invention shown on Figs. 8 and 9, the lifting member 2 is pivotally mounted in the base 5 of the supporting member 1 on a pivot 30, which extends transversely and loosely through the opening 13 in the rear end of the lifting arm 10 of the lifting member 2 and through horizontal slots 31 in the base fork arms 7, respectively, and nuts 32 are threaded on the outer ends of said pivot and washers 33 are fitted on said pivot between said nuts, respectively, and the outer sides of said fork arms, so that said pivot 30 may be adjustably secured in any position in said slots 31 upon tightening the nuts 32 against the washers 33 and said washers against the outer sides of the base fork arms 7, for adjustably pivoting the lifting member 2 in the supporting member 1, with the handle 11 of said lifting member positioned adjacent to or variably spaced from the handle 6 of said supporting member. The further the handle 11 is spaced from the handle 6 the greater the lifting movement of the handle 11 and the lifting arm 10 of the lifting member 2, and consequently the greater the lifting action and effect of said lifting arm against the toe boxing of a shoe.

In the modification of my invention shown in Figs. 10, 11 and 12 there is no bridge 9 in the base 5 or notch 15 in the lifting arm 10 for limiting the return movement of said lifting arm in its initial position, but a pair of flanges 35 are formed on the forward end portion of the lifting arm 10 of the lifting member 2 at the sides, respectively, of said arm, to be received in the rabbets 36 in the upper surface of the forward end portions of the base fork arms 7, respectively, of the supporting member 1, and to engage the lower walls 37 of said rabbets, respectively, to

limit said return movement of the lifting member 2 in its initial position. The flanges 35 are formed on the forward end portion of the lifting arm 10 with their upper surfaces flush with the upper surfaces of said lifting arm, providing said lifting arm with a widened lifting end 38 for lifting the toe boxing of a shoe.

I claim:

1. A shoe toe lifter including a supporting member and a lifting member pivoted to said supporting member, said supporting member comprising a base and a handle upstanding forwardly from said base, and said lifting member comprising a lifting arm and a handle upstanding forwardly from said lifting arm to be gripped, together with said handle of said supporting member, for swinging said lifting member, so that its lifting arm may engage and lift the toe boxing of a shoe.

2. A shoe toe lifter as claimed in claim 1 including a spring for normally maintaining said lifting member in its initial non-lifting position.

3. A shoe toe lifter as claimed in claim 1 including a spring interposed between the handles of the supporting member and the lifting member for normally maintaining said lifting member in the initial non-lifting position.

4. A shoe toe lifter including a supporting member and a lifting member, said supporting member comprising a forked base and a handle upstanding forwardly from the rear end of said base at the junction of the fork arms of said base, said lifting member comprising a lifting arm and a handle upstanding forwardly from the rear end of said lifting arm, said lifting member being pivoted at the rear end of the lifting arm to said forked base in the crotch of said base, with said lifting arm extending between the fork arms of said base.

5. A shoe toe lifter as claimed in claim 1 including a spring interposed between the handles of the supporting member and the lifting member for normally maintaining said lifting member in its non-lifting position.

6. A shoe toe lifter as claimed in claim 1 including an adjustable engaging head mounted on the forward end of the lifting arm of the lifting member.

7. A shoe lifter as claimed in claim 1 including an engaging head formed with a depending threaded shank for engaging a threaded opening in the forward end of the lifting arm of the lifting member.

8. A shoe toe lifter including a supporting member and a lifting member, said supporting member comprising a base and a handle upstanding forwardly from said base, said lifting member comprising a lifting arm and a handle upstanding forwardly from said lifting arm, and means for adjustably pivoting said lifting member to said supporting member to vary the swinging movement of said lifting member and the effective lifting movement of its said lifting arm.

9. A shoe toe lifter including a supporting member and a lifting member, said supporting member comprising a forked base and a handle upstanding from the crotch end of said base, the fork arms of said base being provided with aligned horizontal slots, respectively, extending laterally therethrough, said lifting member comprising a lifting arm and a handle upstanding from the rear end of said lifting arm, said lifting arm being provided with an opening extending laterally through its rear end, a pivot extending through said slots in said base fork arms and ex-

tending loosely through said opening in said lifting arm for pivoting said lifting member in said supporting member with said lifting arm between said base fork arms, and nuts threaded on the outer ends, respectively, of said pivot for engaging said base arms and securing the ends of said pivot in said base arms in different positions in said slots, for adjustably pivoting said lifting member in said supporting member with the handle of said lifting member at varying distances from the handle of said supporting member, for varying the lifting movement of said lifting arm.

10. A shoe toe lifter including a supporting member and a lifting member, said supporting member comprising a forked base and a handle upstanding from the rear end of said base at the junction of the forked arms of said base, said

5 lifting member comprising a lifting arm and a handle upstanding from the rear end of said lifting arm, said lifting member being pivoted at the rear end of the lifting arm to said forked base in the crotch of said base, with said lifting arm extending between the fork arms of said base, a pair of flanges formed on the sides, respectively, at the forward end of said lifting arm, and the forward end portions of the base fork arms being formed in their upper surfaces with rabbets, respectively, to receive said flanges, respectively, to limit the return movement of said lifting member in its initial position.

15 11. A shoe toe lifter as claimed in claim 1 including means for limiting the return movement of said lifting member in its initial position.
